ICE CRUSHER

Thomas W. Kellogg, Newport Beach, Calif., and Henry J. Talge, Kansas City, Mo., assignors to Dazey Products Company, Kansas City Mo., a corporation of Missouri

Filed Apr. 21, 1966, Ser. No. 1,961

Term of patent 14 years

(Cl. D89—1)

FIGURE 1 is a perspective view showing the front and one side of an ice crusher, showing our new design; FIG. 2 is a rear elevational view thereof; FIG. 3 is a side elevational view thereof; and FIG. 4 is a top plan view of an ice crusher.
We claim:
The ornamental design for an ice crusher, as shown.
